UNITED STATES PATENT OFFICE

2,078,163

EVAPORATOR FOR REFRIGERATING MACHINES

Ralph F. Roider, Schenectady, N. Y., assignor to
General Electric Company, a corporation of
New York

Application July 1, 1936, Serial No. 88,358

10 Claims. (Cl. 62—126)

My invention relates to evaporators for refrigerating machines.

It is an object of my invention to provide an improved evaporator of the flooded type for refrigerating machines which shall have one portion operating at low temperature for receiving ice trays and the like, and another portion operating at a higher temperature for cooling the food compartment of a refrigerator cabinet with minimum dehydration of food therein.

Another object of my invention is to provide an improved evaporator of the flooded type having a quick freezing portion for freezing water, desserts and the like, and a higher temperature portion for cooling the air circulated through the food compartment of a refrigerator cabinet in order to minimize the reduction of the humidity of the air in the food compartment.

Another object of my invention is to provide a flooded evaporator for refrigerating machines having an improved arrangement for providing circulation of liquid refrigerant about a freezing compartment and for maintaining a relatively undisturbed body of liquid refrigerant in another portion of the evaporator for cooling a food compartment of a refrigerator cabinet.

Further objects and advantages of my invention will become apparent as the following description proceeds, and the features of novelty which characterize my invention will be pointed out with particularity in the claims annexed to and forming a part of this specification.

For a better understanding of my invention, reference may be had to the accompanying drawing, in which Fig. 1 shows a household refrigerating machine provided with an evaporator embodying my invention; Fig. 2 is a sectional view on the line 2—2 of Fig. 1, showing a fragmentary plan view of the evaporator and freezing compartment; and Fig. 3 is an enlarged perspective view of a portion of the evaporator showing the arrangement for producing a circulation of refrigerant about the freezing chamber thereof.

Referring now to the drawing in Fig. 1, I have shown a household refrigerating machine comprising a cabinet 10 having a thermally insulated top 11 on which is mounted a refrigerating machine. The refrigerating machine includes a casing 12 having a motor and a compressor arranged therein, a condenser 13 having a refrigerant passage 14 and an evaporator 15 mounted below the top 11 and arranged partly within a thermally insulated freezing compartment 16 and partly within the food compartment 17 of the cabinet 10. Gaseous refrigerant is compressed

by the operation of the motor driven compressor within the casing 12 and is discharged into the condenser passage 14, where it is cooled by the natural draft circulation of air over the condenser 13 and is liquefied. The liquefied refrigerant flows 5 into a receiver or float valve chamber 18 through a connection 19. When a predetermined quantity of liquid refrigerant has collected in the float chamber 18, the float therein rises and the refrigerant flows through a connection 20 into the 10 evaporator 15. The liquid refrigerant in the evaporator is vaporized by the absorption of heat from the air within the cabinet and from food or other articles therein and the vaporized refrigerant collects in a cylindrical header 21. The 15 vapor is withdrawn from the header above the level of liquid refrigerant therein through a connection 22 and returned to the compressor in the casing 12.

The evaporator 15 is constructed of sheets of 20 metal 23 and 24, having indentations or corrugations therein and being secured together about their edges and between their indentations by welding, brazing or in any other suitable manner. The header 21 is also formed by indentations in 25 the sheets 23 and 24. The evaporator comprises an upper freezing portion or chamber having conduits 25 communicating with the header 21 for circulating liquid refrigerant therearound, and a second portion depending from the first portion 30 and comprising a plurality of upright refrigerant conduits 26. The conduits 25 and 26 communicate with each other through a manifold 27 extending across the side of the freezing chamber in the lower portion thereof. A tube 28 is 35 arranged within the manifold 27 and communicates with the connection 20, so that liquid refrigerant admitted to the evaporator passes from the connection 20 into the tube 28 and thence into the conduits 25 through a plurality of outlet orifices 29 arranged in alignment with the centers of the conduits 25. These orifices inject the refrigerant upwardly into conduits 25, and thereby produce a rapid circulation of liquid refrigerant around the freezing chamber through 45 the conduits 25. The header 21 is maintained about half full of liquid refrigerant so as to flood the evaporator and to maintain the conduits 25 and 26 filled with liquid refrigerant. The liquid refrigerant in the conduits 26 is relatively undisturbed, since the lower ends of these conduits are closed and no circulating path is provided for the refrigerant. It is, therefore, apparent that the rate of absorption of heat from the air surrounding the evaporator, or from articles placed 50 55

thereon, will be greater adjacent the conduits 25 in which there is a rapid circulation of the refrigerant than adjacent to the conduits 26 in which the refrigerant is more or less undisturbed. Furthermore, since the liquid refrigerant in the conduits 26 is maintained relatively undisturbed it may become superheated, thereby tending to maintain the temperature of the depending portion of the evaporator higher than that surrounding the freezing chamber. The inlet tube 28 may also be arranged to restrict the opening between the conduits 25 and 26 to increase the resistance of flow of refrigerant therebetween and permit a somewhat greater pressure to be maintained in the conduits 26. By selecting the dimensions and proportions of the several parts of the evaporator, temperature differences within a range of 2° F. to 20° F. may be obtained between the depending portion and the freezing chamber. The insulated compartment 16 is arranged to surround the portion of the evaporator containing the conduits 25 and thereby provide a compartment for operation at low temperatures for the freezing of water, desserts and the like. The conduits 26 of the evaporator extend outside the compartment 16 into the main food compartment 17 of the cabinet 10 which is cooled by the natural circulation of air over the conduits 26. Since the air in the food compartment is not circulated continuously over the freezing portion of the evaporator there is less condensation of moisture from the air and less moisture is therefore removed from the food in the cabinet. An evaporator constructed as described thus makes possible the operation of a domestic refrigerator with higher humidity of the cabinet air and yet provides adequate ice freezing capacity. Some circulation of air through the compartment 16 may be desirable and, for this reason, I have provided elongated openings 30 and 31 at the top and bottom, respectively, of the compartment 16 through which air may circulate between the compartments 16 and 17, and I have also provided pivotally mounted and adjustable dampers 32 and 33 for controlling the openings 30 and 31, respectively, so that the amount of air circulating through the openings may be varied.

During the operation of the flooded evaporator shown, a rapid circulation of liquid refrigerant is provided around the freezing chamber through the conduits 25 by operation of the injectors 29 and any articles such as trays of water placed adjacent the conduits 25 will be cooled rapidly. The relatively undisturbed body of liquid refrigerant in the conduits 26 is available for absorbing heat from the air within the food compartment 17, and any refrigerant vaporized in the conduits 26 will rise to the manifold 27 and thence to conduits 25 and the header 21, thereby assisting the injectors 29 in producing a circulation of refrigerant through the conduits 25. The liquid refrigerant with entrained vaporized refrigerant will flow from the manifold 27 to the header 21, where the vaporized refrigerant will rise above the level of liquid refrigerant in the header. The rate of absorption of heat through the conduits 26 will be relatively low since no continuous circulation of liquid refrigerant therein may be maintained. It is, therefore, apparent that I have provided a flooded evaporator having a portion available for freezing purposes and a second portion which may be employed to cool a food compartment of a refrigerator, without requiring an undesirable reduction of the temperature of the air in the food

compartment due to the operation of the freezing portion of the evaporator.

While I have shown and described my invention in connection with a household refrigerating machine, it will be understood that it is applicable to other types of refrigerating machines, and I do not desire my invention to be limited to the particular construction shown and described, and I intend in the appended claims to cover all modifications thereof which do not depart from the spirit and scope of my invention.

What I claim as new and desire to secure by Letters Patent of the United States is:

1. A flooded evaporator for refrigerating machines comprising means including a plurality of 15 conduits for forming a freezing chamber, means for injecting refrigerant upwardly into a plurality of said conduits on one side of said chamber to produce a circulation of refrigerant around said chamber through said conduits, means depending from said conduits for maintaining a relatively undisturbed body of liquid refrigerant in communication with the lower portion of said conduits, and means for withdrawing gaseous refrigerant from said evaporator. 20

2. A flooded evaporator for refrigerating machines comprising means including a plurality of conduits for forming a freezing chamber, a header arranged above said conduits and communicating therewith, means for injecting refrigerant upwardly into a plurality of said conduits on one side of said chamber to produce a circulation of refrigerant around said chamber through said conduits, means including a plurality of conduits depending from said first-mentioned conduits for 30 providing a portion of said evaporator filled with relatively undisturbed liquid refrigerant, and means for withdrawing gaseous refrigerant from said header. 35

3. A flooded evaporator for refrigerating machines comprising means including a plurality of conduits for forming a freezing chamber, a manifold communicating with the lower portions of said conduits near one side thereof, means arranged in said manifold for injecting refrigerant 40 upwardly into a plurality of said conduits to produce a circulation of refrigerant around said chamber through said conduits, means depending from said conduits for maintaining a relatively undisturbed body of liquid refrigerant in communication with the lower portion of said conduits and means for withdrawing gaseous refrigerant from said header. 45

4. A flooded evaporator for refrigerating machines comprising means including a plurality of 55 conduits for forming a freezing chamber, a manifold communicating with the lower portions of said conduits near one side thereof, means arranged in said manifold for injecting refrigerant upwardly into a plurality of said conduits to produce a circulation of refrigerant around said chamber through said conduits, means including a plurality of conduits depending from said manifold and communicating therewith for maintaining a quantity of relatively undisturbed liquid refrigerant in 60 communication with said first-mentioned conduits, and means for withdrawing gaseous refrigerant from said header. 65

5. A flooded evaporator for refrigerating machines comprising means including a plurality of 70 conduits for forming a freezing chamber, a body of heat insulating material surrounding said chamber, a header arranged above said conduits and communicating therewith, means for injecting refrigerant upwardly into a plurality of said 75

conduits on one side of said chamber to produce a circulation of refrigerant around said chamber through said conduits, means including a plurality of conduits depending from said first-mentioned conduits for providing a portion of said evaporator filled with relatively undisturbed liquid refrigerant, said depending conduits extending outside of said body of insulating material, and means for withdrawing gaseous refrigerant from 10 said header.

6. In a refrigerating machine including a thermally insulated cabinet, a thermally insulated compartment arranged within said cabinet, a flooded evaporator comprising means including a 15 plurality of conduits for forming a freezing chamber and arranged in said compartment, means including ventilating openings in said compartment for circulating air from said compartment into said cabinet, means including a plurality of conduits depending from said first-mentioned conduits and extending outside said compartment for providing a portion of said evaporator filled with relatively undisturbed liquid refrigerant, and means for withdrawing 20 gaseous refrigerant from said header.

7. A flooded evaporator for refrigerating machines comprising means including a plurality of conduits for forming a freezing chamber, means for injecting refrigerant into a plurality of said conduits to produce a circulation of refrigerant around said chamber through said conduits, means depending from said conduits for maintaining a relatively undisturbed body of liquid refrigerant in communication with the 30 lower portion of said conduits, and means for withdrawing gaseous refrigerant from said evaporator.

8. A flooded evaporator for refrigerating machines comprising means including a plurality of conduits for forming a freezing chamber, a 40

header arranged above said conduits and communicating therewith, means for injecting refrigerant into a plurality of said conduits to produce a circulation of refrigerant around said chamber through said conduits, means including a plurality of conduits depending from said first-mentioned conduits for providing a portion of said evaporator filled with relatively undisturbed liquid refrigerant, and means for withdrawing gaseous refrigerant from said header. 10

9. A flooded evaporator for refrigerating machines comprising means including a plurality of conduits for forming a freezing chamber, a manifold communicating with the lower portions of said conduits, means arranged in said manifold 15 for injecting refrigerant into a plurality of said conduits to produce a circulation of refrigerant around said chamber through said conduits, means depending from said conduits for maintaining a relatively undisturbed body of liquid 20 refrigerant in communication with the lower portion of said conduits, and means for withdrawing gaseous refrigerant from said header.

10. A flooded evaporator for refrigerating machines comprising means including a plurality of 25 conduits for forming a freezing chamber, a body of heat insulating material surrounding said chamber, a header arranged above said conduits and communicating therewith, means for injecting refrigerant into a plurality of said conduits 30 to produce a circulation of refrigerant around said chamber through said conduits, means including a plurality of conduits depending from said first-mentioned conduits for providing a portion of said evaporator filled with relatively 35 undisturbed liquid refrigerant, said depending conduits extending outside of said body of insulating material, and means for withdrawing gaseous refrigerant from said header.
